UNITED STATES PATENT OFFICE.

FREDERICK NUESKE, OF NEW YORK, N. Y., ASSIGNOR TO JULIUS NUESKE & SONS, INC., OF NEW YORK, N. Y., A CORPORATION OF NEW YORK.

PATTERN-LATHE.

1,854,453.

Specification of Letters Patent. Patented Sept. 28, 1920.

Application filed September 19, 1919. Serial No. 324,735.

To all whom it may concern:

Be it known that I, FREDERICK NUESKE, a citizen of the United States, and a resident of the city of New York, borough of Queens, 5 in the county of Queens and State of New York, have invented a new and Improved Pattern-Lathe, of which the following is a full, clear, and exact description.

This invention relates to improvements in 10 pattern lathes, an object of the invention being to provide improved means for reciprocating a pattern and the work held in engagement respectively with a fixed pattern disk and a rotary cutter so that the work 15 will be shaped by the cutter in accordance with the pattern.

A further object is to provide improved 20 means for mounting the work and the pattern, improved means for reciprocating the work and the pattern and imparting rotary motion to both, and provide improved 25 means for spring pressing a pattern against a fixed pattern disk and the work against a rotary cutter during their reciprocating movement.

A further object is to provide improved 30 means for transmitting motion to the pattern, the work, and the rotary cutter, which enables a free manipulation of all of the parts, as occasion may require.

A further object is to provide improved 35 means for stopping the reciprocating motion of the pattern and the work to allow the insertion of new work after an operation is completed.

A further object is to provide improved 40 means for spring pressing the pattern and the work against the pattern disk and cutter respectively.

A further object is to provide improved 45 driving mechanism which permits the speed of the several movements to be adjusted at will so as to give the desired results.

With these and other objects in view the 50 invention consists in certain novel features of construction, and combinations and arrangements of parts, as will be more fully hereinafter described and pointed out in the claims.

55 In the accompanying drawings—

Figure 1 is a top plan view illustrating my improved machine;

Fig. 2 is a view in side elevation;

Fig. 3 is an enlarged fragmentary plan

view showing the mechanism for throwing 55 the reciprocating driving means out of operation;

Fig. 4 is a view in section on the line 4—4 of Fig. 3;

Fig. 5 is a view in section on the line 60 5—5 of Fig. 6;

Fig. 6 is a view partly in elevation and partly in section illustrating the work and pattern supports; and

Fig. 7 is a view in section through the 65 cutter.

1 represents a supporting table having two heads 2 and 3 thereon. The head 2 is secured to a base 4 which has a slot 5 therein and a set screw 6 located in the slot and 70 securing the base and head at any desired lateral adjustment. The head 3 is supported on a base 7 which is adjustable laterally and longitudinally by means of set screws 8 and 9 respectively, and clamping 75 arms 10 secure the base 7 at the desired position of adjustment.

The head 2 supports a rotary shaft 11, while the head 3 supports and normally 80 clamps a rotary shaft 12. On the shaft 11 a rotary cutter 13 is secured and pattern follower 14 is secured on the shaft 12, said shafts being in alinement and the cutter and follower being of the same diameter. A drive pulley 15 is provided on the shaft 85 11 and receives motion in any approved manner to turn the cutter. A pulley 16 is provided on the shaft 12 to turn the shaft when the latter is released from clamping action and the cutter and the pattern follower 90 are reversed, which is desirable in the making of a new pattern.

A protecting hood 17 partially incloses the cutter 13 and a base 18 of said hood is secured to the table 1 by set screws 19, and 95 said hood has a tubular extension 20 to which an air hose, not shown, may be connected to draw off the shavings.

A pivoted frame 21 is supported on a shaft 22 and the latter is mounted in bearings 70 on a reciprocating plate 71, said plate guided in its movement by strips 72 secured to the table 1.

The pivoted frame 21 is made with three alined bearings 23, 24 and 25. Rotary 105 chucks 26 and 27 are supported in the bearings 24 and 25 respectively and support a pattern 28 between them. A chuck 29 is

supported at the other end of bearing 24 and the work 30 is held between the chuck 29 and a center 31, the latter mounted to move longitudinally in a sleeve 32, said sleeve secured in the bearing 23 by means of a set screw 33.

A bracket arm 34 is secured on the sleeve 32 and an L-shaped lever 35 is pivotally connected at its lower end, as shown at 36, to 10 the lower end of the arm 34. A link 37 connects the intermediate portion of the lever 35 with a bifurcated head 38 on the end of rod 31. A coiled spring 39 connects the upper portion of the lever 35 with the 15 arm 34 and exerts an inward pressure on the lever and on the center 31 to engage the work and hold the latter in proper position. When it is desired to release the work, it is simply necessary to swing the upper 20 end of the lever 35 outwardly withdrawing the center 31, as will be readily understood.

A fixed arm 40 is secured to the guide plate 71 and has a slot 41 at its upper end. A sleeve 42 is pivotally mounted in the slot 25 41 by means of screws or pins 43 and supports a plunger rod 44, the inner end of said plunger rod normally engaging in a notch 45 in the bearing 24. A shoulder 46 is provided on the rod 44 and a coiled spring 47 30 is located around the rod between the shoulder 46 and the sleeve 42 exerting an inward pressure on the rod so as to exert a continuous inward pressure on the frame 21 to hold the pattern and work against the 35 pattern follower and cutter respectively. A finger hold 48 is provided on the outer end of the rod 44.

When it is desired to release the frame from its operative position, it is simply necessary to withdraw the rod 44 from the 40 notch 45 and swing the rod at an angle, the pins or screws 43 operating as pivots. The frame 21 can then be swung out of the way of the pattern follower and cutter, as will be understood.

A drive shaft 49 is supported in bearing brackets 50 at one side of the table 1 and is provided at its ends with friction disks 52, and 53 respectively. A bracket 54 is secured to one end of the table 1 and is provided with bearings 55 and 56 affording mounting for a shaft 57. A rod 58 is secured to the brackets 55 and 56 and located parallel to the shaft 57.

55 A bifurcated bracket 59 is mounted to slide on the rod 58 and secured in position of adjustment by means of a set screw 60. A friction wheel 61 is keyed to the shaft 57 and located in the bracket 59 and engaging the face of disk 53 so that by reason of the adjustment of the bracket 59, the wheel 61 can be moved toward or away from the center of the disk 53 to vary the speed of transmission.

A worm 62 on one end of shaft 57 meshes 65 with a worm wheel 63 which is keyed on the shaft 22 so that the latter is free to reciprocate through the wheel 63 and the parts are held in proper relative positions by means of bearing brackets 64 which extend 70 laterally from the bearing bracket 56.

A pinion 65 is secured on the shaft 22 and meshes with an idle pinion 66 located on a stud 67 carried by frame 21 and meshes with a gear wheel 68 on a short shaft 69 75 carrying the chuck 27. It is, of course, to be understood that the several chucks supporting the pattern and the work are in alinement and are connected so that when the shaft 69 is driven, the pattern and the 80 work are likewise revolved.

A bracket 73 is secured to the opposite end of table 1 and has a bearing 74 for a vertical shaft 75. A crank disk 76 is secured on the upper end of shaft 75 and a 85 link 77 connects the crank disk with the reciprocating plate 71 so that as the disk revolves a reciprocating motion is imparted to the plate. A hand wheel 78 is provided on the lower end of the shaft 75 so as to 90 permit a manual manipulation to position the parts as may be desired.

The crank pin 76^a on disk 76 is adjustable in a T-slot 76^b and the link 77 comprises two members 77^a and 77^b connected by screws 95 77^c. The screws are positioned in slots 77^d in the link member 77^a and screwed into member 77^b so that the length of the link can be adjusted.

This adjustment of the movement imparted to the plate 71 is to give the desired movement according to the work desired.

A worm wheel 79 is secured on the shaft 75 and is driven by a worm 80 secured on a shaft 81, the latter mounted in bearings 105 94 on a pivot plate 83. This pivot plate is guided in its pivotal movement by means of guide strips 93 at the ends thereof and is adapted, when moved, to move the worm 80 out of mesh with worm wheel 79. The 110 bearings 94 support a rod 88 on which a bracket 86 similar to the bracket 59 is mounted and secured by means of a set screw 87. A friction wheel 85 is secured on the shaft 81 in the bracket 86 and engages the face of the friction disk 52.

A lever 89 is pivotally supported on a bracket arm 90 and has its inner end connected by a link 91 to the pivot plate 83 and a stop pin 92 on said plate limits the movement of the link 91 in one direction and in this position of the link, the worm 80 is in mesh with the worm wheel 79. When the lever 89 is swung to the right of Fig. 3, the plate 83 will be moved on its pivot 84 to 120 move the worm 80 away from the worm wheel 79 so that the reciprocating motion of the plate 71 is stopped and the plate and

parts carried thereby can be manually moved at will until the worm 80 is again moved in mesh with the worm wheel.

- The operation is as follows: The pulley 15 is driven to continuously revolve the cutter 13. The drive shaft 49 transmits motion from disk 53, wheel 61, shaft 57, worm 62, worm wheel 63, shaft 22, and pinions 65, 66 and 68 to revolve the pattern 28 and the work 30, as above explained. The drive shaft 49, through the medium of disk 52, wheel 85, shaft 81, worm 80, worm wheel 79, shaft 75, crank disk 76, and link 77, imparts a continuous reciprocating motion to the plate 71. The spring pressed rod 44 exerts a continuous lateral pressure against the frame 21 to hold the pattern and the work against the pattern follower and the cutter respectively. It will thus be noted that while the pattern follower is stationary and the cutter has rotary motion, it is held against movement in any other direction while the pattern and the work are continuously revolved, are held in contact with the pattern follower and the cutter respectively, and are given a continuous longitudinal reciprocating motion so that the cutter quickly cuts the work in exact conformity with the pattern.
- When it is desired to cut a new pattern, the cutter 13 and the pattern follower 14 have their positions reversed. The finished device or the pattern, as the case may be, is then located between the chuck 29 and the chuck rod 31 and the work is located between the chucks 26 and 27 so that the new pattern will be cut exactly like the old pattern or the article.

Various slight changes may be made in the general form and arrangement of parts described without departing from the invention, and hence I do not limit myself to the precise details set forth but consider myself at liberty to make such changes and alterations as fairly fall within the spirit and scope of the appended claims.

I claim:

1. The combination in a lathe with a pattern follower and a cutter, of a reciprocable work and pattern support, means on the support holding the pattern against the follower and the work against the cutter, a rotatable shaft, a crank disk, a crank pin adjustable on the crank disk, and a link connecting the crank pin and the support for reciprocating the support upon the rotation of the disk.

2. The combination in a lathe with a pattern follower and a cutter, of a reciprocable work and pattern support, means on the support holding the pattern against the follower and the work against the cutter, a rotatable shaft, a crank disk having a groove extending across the center thereof, a crank

pin adjustably secured in said groove, and a link connecting said crank pin with the support for reciprocating the support upon rotation of the disk.

3. The combination in a lathe with a pattern follower and a cutter, of a reciprocable work and pattern support, means on the support holding the pattern against the follower and the work against the cutter, a rotatable shaft, a crank disk, a crank pin adjustable on the crank disk, and a link connecting the crank pin and the support for reciprocating the support upon the rotation of the disk, a worm wheel fixed to turn with the crank disk, a driving worm meshing with the worm wheel, and means for moving the worm away from the worm wheel.

4. The combination in a lathe with a pattern follower and a cutter, of a reciprocable work and pattern support, means on the support holding the pattern against the follower and the work against the cutter, a rotatable shaft, a crank disk having a groove extending across the center thereof, a crank pin adjustably secured in said groove, a link connecting said crank pin with the support for reciprocating the support upon rotation of the disk, a worm wheel fixed to turn with the crank disk, a driving worm meshing with the work wheel, and means for moving the worm away from the worm wheel.

5. The combination in a lathe with a pattern follower and a cutter, of a reciprocable work and pattern support, means on the support holding the pattern against the follower and the work against the cutter, a rotatable shaft, a crank disk, a crank pin adjustable on the crank disk, and a link connecting the crank pin and the support for reciprocating the support upon the rotation of the disk, a worm wheel fixed to turn with the crank disk, a driving worm meshing with the worm wheel, and means for moving the worm away from the worm wheel, a drive shaft, and adjustable friction driving means operatively connecting the worm with the drive shaft.

6. The combination in a lathe with a pattern follower and a cutter, of a reciprocable work and pattern support, means on the support holding the pattern against the follower and the work against the cutter, a rotatable shaft, a crank disk having a groove extending across the center thereof, a crank pin adjustably secured in said groove, a link connecting said crank pin with the support for reciprocating the support upon rotation of the disk, a worm wheel fixed to turn with the crank disk, a driving worm meshing with the worm wheel, means for moving the worm away from the worm wheel, a drive shaft, and adjustable friction driving means operatively connecting the worm with the drive shaft.

7. The combination in a lathe with a pattern follower and a rotary cutter, of a reciprocable work and pattern plate, means on the plate supporting the pattern against the follower and the work against the cutter, a rotatable shaft, a crank disk on the shaft, a link connecting the crank disk and the support for reciprocating the support upon rotation of the disk, a worm wheel on said shaft, a pivotal support, a second shaft mounted on said pivotal support, a worm on the second shaft meshing with the worm wheel, and means for moving the pivotal support to move the worm out of mesh with the worm wheel.

8. The combination in a lathe with a pattern follower and a rotary cutter, of a reciprocable work and pattern plate, means on the plate supporting the pattern against the follower and the work against the cutter, a rotatable shaft, a crank disk on the shaft, a link connecting the crank disk and the support for reciprocating the support upon rotation of the disk, a worm wheel on said shaft, a pivotal support, a second shaft

mounted on said pivotal support, a worm on the second shaft meshing with the worm wheel, a lever, a link connecting the lever with the pivotal support whereby the movement of the lever in one direction causes the movement of the pivotal support to move the worm out of mesh with the worm wheel, and a stop pin on the pivotal support limiting the movement of the link in one direction when the worm is in mesh with the worm wheel.

9. The combination in a lathe with a pattern follower and a rotary cutter, of a reciprocable work and pattern support, means on said support for holding the pattern against the pattern follower and the work against the cutter, a rotatable drive shaft, a crank disk, a link connecting the crank disk and support for reciprocating the support upon the rotation of the disk, and adjustable friction driving means between the drive shaft, the crank disk and the pattern and work support whereby reciprocating motion is imparted to the pattern and work.

FREDERICK NUESKE.
